UNITED STATES PATENT OFFICE.

RAYMOND D. SMITH, OF SCARSDALE, NEW YORK, ASSIGNOR, BY MESNE ASSIGNMENTS, TO TREMONT PRODUCTS CORPORATION, OF BOSTON, MASSACHUSETTS, A CORPORATION OF MASSACHUSETTS.

THERMOSTATICALLY-CONTROLLED SOCKET SWITCH.

Application filed December 3, 1920. Serial No. 428,100.

To all whom it may concern:

Be it known that I, RAYMOND D. SMITH, a citizen of the United States, and resident of Scarsdale, in the county of Westchester and State of New York, have invented certain new and useful Improvements in Thermostatically-Controlled Socket Switches.

One object of the present improvement is the provision of a pull chain control in an electric lamp socket or other type of switch employing a controlling thermostat to automatically delay the circuit breaking action when the switch has been manually actuated to extinguish the light.

15 The present invention also includes novel features of arrangement and construction in the switch mechanism per se, aimed to render a socket switch with the above feature more durable in use and cheaper to manufacture.

20 Much of the novelty here concerned, constitutes improvements specifically applicable in the form of thermostatically controlled socket switches such as is illustrated and described in United States Patent No. 1,328,478 granted Jan. 20, 1920 wherein the switch controlling thermostat operates a latch, and specifically constitutes such latch, normally positioned to intercept the circuit-breaking movement of one of the switch contact

30 members.

A general simplification of the contact controlling mechanism is contemplated by the present improvements whereby much of the requirement for skill and accuracy in assembling shall be eliminated. The present improvement, furthermore, provides a switch mechanism wherein there is no possibility of leaving the contact parts in a position to arc or burn.

40 A possible and preferred embodiment of the present invention is illustrated in the accompanying sheets of drawings wherein, Fig. 1 is an elevation of the complete socket switch with casing and lower threaded shell cut away to better show the interior parts. Fig. 2 is a section taken on the plane 2—2 of Fig. 1 looking in the direction of arrows. Fig. 3 is a view looking in the same direction as Fig. 2 but taken in section on the planes 3—3 in Fig. 1. Fig. 4 shows details of construction and a different position of certain parts in Fig. 2. Fig. 5 is a fragmentary view looking from the left at Fig. 1, certain parts above the thermostat and con-

tacts in said Fig. 1 being taken in central vertical section to more clearly show their construction. Fig. 6 is a diagram of electrical connections with the switch parts indicated in their "full off" position. Fig. 7 is a similar diagram showing the switch parts in full "on" position. Fig. 8 is a similar view showing parts as they are positioned directly after the "off" actuation of the pull chain, but before the circuit has been automatically broken. Fig. 9 is a perspective downward view of the thermostat, its co-operating contact member, and the bracket on which both are mounted. Fig. 10 is a perspective upward view of the pull chain operated segment and contact operating cam assembled therewith. Fig. 11 is a detailed perspective view of the pivot washer enlarged. Fig. 12 is a similar perspective view of the pivot screw. Fig. 13 shows on a greatly enlarged scale the anchorage of a lead wire to an insulated strap about the thermostat. Fig. 14 shows the anchorage to this same strap of a fine resistance wire which heats the thermostat. Fig. 15, shows the anchorage for the resistance wire at its grounded end. Fig. 16 shows the developed shape of the thin, soft sheet metal strap for electrical connection of the fine resistance wire.

Each part when appearing in different views of the drawings is designated by the same reference character.

In Fig. 1 the usual upper porcelain button 10 and lower porcelain button 11 are secured in spaced relation by four bracket members as follows: the main contact bracket 12, the auxiliary contact bracket 13, the center bracket 14, and the thermostat bracket 15, each of which engages with suitable locating grooves on both the upper and lower porcelain buttons.

45 The main contact bracket 12 carries the main spring-leaf contact 16. The auxiliary contact bracket 13 carries the auxiliary spring-leaf contact 17, to the end of which is secured an insulating facing 18 by eyelet 19 or other suitable form of fastening. The center bracket 14 is plain, serving to electrically connect the upper central contact washer 20 through screw 21 with the lower central contact tongue 22 through screw 23. This center bracket thus forms one side of the line through the socket indicated by the numeral 24 in Figures 6 to 8 inclusive.

The thermostat 25 and co-operating spring-leaf contact 26 are riveted at different places to the bracket 15, as more plainly shown in Figure 9, and by means of the 5 preferred construction of a rectangular riveting boss struck up from the metal of the bracket itself.

The thermostat 25 carries a tight fitting sleeve 28 of suitable insulating material, such 10 as asbestos paper, on which is wound the required number of turns of a small resistance wire 29 in insulated relation to the thermostat and anchored at each end in a manner hereinafter to be described.

15 The thermostat bracket 15 has a centrally disposed terminal 30, on which is mounted by means of a novel pivotal construction, the pull-chain operated cam 31, which co-operates with both contacts 17 and 26 for a 20 purpose and in a manner hereinafter fully described. Up-standing ear portions 32, 32 (Fig. 10) of the cam 31 are rigidly secured to thrust plate 33 and to a superposed fibre segment 34, by two eyelets, 35, 35, as plainly 25 shown in Figure 10, where the fibre segment 34 is shown as also provided with a peripheral chain guide 36 having bent terminals 37 at each end containing an anchorage slot 38 for the ball chain. The chain 30 guide 36 is fastened to the fibre segment 34 by means of up-standing prongs 39 (see Figure 5) which project through corresponding slots in the fibre segment and are bent over flat on the upper surface of same, in the well-known manner.

Two operatively separate chains 42 and 43 are employed for oscillating the fibre segment 34 by alternate pulling thereon, the customary bell mouth 40 being provided, of 40 a size adequate to form a common guide and outlet for both chains so that the latter can move therethrough in respectively opposite directions at the same time and without interference. Slide terminal 41 is attached to the "off" chain 42, through the other barrel of which the "on" chain 43 loosely slides, the latter having the usual ball terminal 44 for convenient manipulation.

45 The novel hinge construction, hereinbefore referred to, by which the cam structure 31, 33, 34 (see Fig. 10) is pivotally mounted upon the centrally disposed terminal 30 of thermostat bracket 15 (see Fig. 9) consists of the pivot screw 45 shown in enlarged detail in Fig. 12 and the spring-armed pivot washer 46 shown in enlarged detail in Fig. 11, and carrying the downward bent lock tongue 47 for engagement with the notch 48 in bracket terminal 30.

50 The parts just described assemble in the following manner. First, washer 46 is placed flat against the upper surface of bracket terminal 30 with tongue 47 engaging notch 48. Screw 45 is then set up in 55 the tapped hole 99 in bracket terminus 30

so that the flattened head 100 of screw 45 engages the hub portion 101 of the washer 46 securing the latter in place. The reduced end 102 of screw 45 then protrudes below the bracket terminus 30 an amount preferably 70 equal to the thickness of the sheet metal from which cam 31 is formed. The space between the seating portion 103 of cam 31 and the thrust plate 33, however, is slightly less than 75 is the normal overall distance from the lower face of bracket terminus 30 to the highest point of the spring arms 104, 104 of washer 46 so that in sliding the cam and segment structure 31, 33, 34 onto its pivot the spring arms 104 are depressed sufficiently to allow 80 the seat portion 103 of cam 31 to slide past the protruding end 102 of screw 45 until the pivot hole 105 in cam 31 comes to register with the said end 102 of screw 45, at which 85 time the action of spring arms 104 snaps the cam seat 103 up against the lower face of bracket terminus 30 and into its normal assembled position shown in Figs. 1 and 5;— the spring arms 104, thereafter, acting to 90 keep the cam 31 in place and pivoted on the end of screw 45 and resiliently pressed upwardly against the bracket terminus 30. This novel hinge construction is obviously 95 usable in other connections than electric switches but is of particular advantage so used because giving a smooth and positive pivotal connection offering desired frictional resistance and requiring for its assemblage by unskilled labor no tools other than the 100 fingers of the operator. No reliance is had upon the workman's skill to properly adjust tension, and the relation of the parts when 105 assembled is assuredly accurate.

It is pointed out in connection with the pivotal construction above described that 110 the bending of cam ears 32, 32 respectively in different angular planes gives more strength and rigidity with the desirable thin gauge metal employed than would otherwise be possible, and that the presence of thrust plate 33 relieves fibre segment 34 from all 115 flexural strain, being itself fully insulated by the fibre piece from possible contact with electrically alive parts secured to the upper porcelain 10. A removable screw such as 45 need not necessarily be employed to form the pivot projection 102, as same could equally well be formed by metal struck down from the bracket terminal 30, or in other suitable 120 manner.

125 Figures 13 and 14 show the preferred method employed for anchoring the insulated end of delicate resistance wire 29 for protecting the same, while insuring good mechanical and electrical contact. A thin strap 115 is employed which is originally of the shape shown in Fig. 16, and which bends over the insulating jacket or sleeve 28 and is locked by bending over tongue 116, around which the copper lead wire 130

117 is wound before pressing into place. The other end of lead wire 117 extends to and is clamped beneath the top end of auxiliary contact bracket 13 as plainly shown in Fig. 9 this lead wire 117 being coarser and stronger than the resistance wire to avoid the fragility which would result were the fine hair-like resistance wire 29, itself, extended to contact with bracket 13. The resistance wire 29 is wound about another tongue 118 of the same strap 115 on the opposite side of the thermostat, which when pressed down against the thermo jacket gives secure electrical contact and protective mechanical fastening for this end of the resistance wire. The other end of resistance wire 29 is wound under the protruding ends of a thin staple 119 inserted through a narrow slot in the thermostat, these ends being then pressed down to secure the wire in place and to establish good electrical contact for grounding to the thermostat.

The switch mechanism above described, including the porcelain buttons 10 and 11, 25 is capped by a male screw shell 106 and retaining porcelain block 107, said screw shell 106 having electrical connection with main contact bracket 12 by means of screw 108 but being insulated from all other holding 30 screws penetrating upper porcelain button 10. Depending from lower porcelain button 11 is the usual female screw shell, or lamp receptacle, 109 having electrical connection with the auxiliary contact bracket 13 by 35 means of the screw 110 but being insulated from all other fastening screws penetrating lower porcelain button 11.

The switch is enclosed as usual within the casing 111 and paper lining 112, the former 40 being fastened by 2 screws (not shown) which penetrate the casing 111 and screw into tapped holes 113 in bracket members 114 secured in diametrically opposite relation to the upper porcelain 10 while insulated from all electrically alive parts.

The operation of my improved thermostatically controlled socket switch is as follows:

In the full "off" position of the switch, the 50 parts assume the relation in Fig. 6 at which time the chain rider 41 is down and the chain terminal 44 is up,—the pull segment 34 occupying its full line position in Fig. 3 corresponding to the position of cam 31 shown in Fig. 6. To turn the light on, or 55 establish the lamp permanently in circuit, the ball terminal 44 is pulled, swinging the pull segment 34 to its dotted position in Fig. 3 and cam 31 and switch contacts into their 60 relation shown in Fig. 7 where current passes from main contact 16 to contact member 26 to cam 31 to auxiliary contact 17 through bracket 13 and screw 110 to female screw shell 109 to one side of the lamp, re- 65 turning straight through the socket by path

24 (see Figs. 6 to 8) composed of the tongue 22, screw 23, bracket 14, screw 21 and washer 20, as hereinbefore described. When the chain rider 41 is subsequently pulled for extinguishing the lamp the segment 34 is thrown to its full-line position in Fig. 3 and the cam 31 and several contact members assume the relative position shown in Fig. 8 where the thermostat 25 retains contact member 26 in contact with main contact 16 70 while the cam 31 has broken contact with eyelet 19 by sliding on to the insulating facing 18. The only path for the current now is from main contact 16 to contact member 26 to the thermostat 25 through resistance 80 wire 29 to auxiliary contact bracket 13 and thence through the lamp and back through the socket as before, it being seen that here the resistance wire 29 is thrown in series with the lamp and is thereby heated, energizing the thermostat 25 to perform a curvature-opening movement which retracts its free-end from the tip of contact member 26, permitting the latter to snap away from contact 16 into its full "off" position shown in 85 Fig. 6, wherein all circuit through the socket has been broken and the switch is ready for subsequent actuation to turn on the light. An interval of delay is thus interposed between the act of pulling the chain rider 42 90 and the actual circuit breaking action of the switch equal to the time required to heat the thermostat 25 for effecting escapement of the contact member 26. In practice, this time can readily be varied between 15 seconds and two or three minutes through variation of the electrical resistance of wire 29 and of the amount of engagement between the thermostat 25 and the tip end of contact member 26. It is understood that thermostat 100 105 25 possesses sufficient elasticity to enable it to yield when normally cool, like a latch, for permitting the passage of contact member 26 from its position in Fig. 6 to its circuit making position in Fig. 7.

Specific advantages provided by the present improvement reside in the arrangement of auxiliary contact 17 wherein the latter constantly presses against a wiping portion of cam 31 opposing the latter's movement 110 from its position in Fig. 6 to its position in Fig. 7 until the cam has moved well into contact with eyelet 19. The leaving of cam 31 in a position forcing contact member 26 into arcing proximity with main contact 16, is thus impossible, auxiliary contact 17 adding its tendency to that of the normal resiliency in contact member 26, for this purpose, which latter alone is inadequate when made of desirably light gauge spring 115 120 125 metal.

An improvement of equal value is represented in the novel form hereby given to the main contact 16. A spring-leaf contact has heretofore been employed for this pur- 130

pose which performed its necessary yielding to accommodate the latching action of member 26, by flexing resiliently from its point of fastening to bracket 12. The operative tendency of this relation of parts is to decrease the speed of break and cause burning of the contacts with high powered lamps. My improved form for this contact provides two side flanges 120 (see Figs. 2 and 5) rendering contact 16 operatively rigid in its portion from bracket 12 to the ends of these flanges, whereat a bent-over, compound curvature is given the terminal of contact 16 enabling it to flex resiliently between its dotted and full line positions in Fig. 2 which permits the necessary movement of member 26 in sliding contact therewith as will be clear from the drawing. As the movement of contact 16 is, in this arrangement, across the path of movement of member 26, the desirably quick break of the circuit is secured when these two contacts snap apart.

The various parts with their manner of assemblage hereinbefore described are for the most part readily producible from sheet metal through power press production methods making their accuracy dependable and their manufacture economical.

It will be understood that the features of improvement here concerned are of a nature lending themselves to embodiment in many kinds of switches other than electric lamp sockets of the particular form shown and to use with mechanisms for other purposes so that the following claims are in no way intended to limit the forms of the inventions defined to the precise showing in drawings.

What I claim as new is:

- 40 1. A lamp socket switch having a casing and switch operating instrumentalities, the latter including contacts, a thermostat disposed circumferentially in the plane of said contacts a contact-controlling member, a pull-chain-operated segment pivoted to swing in a plane adjacent said thermostat and contacts connected to said member and wholly enclosed within the casing, operatively different chains connected to said segment for oscillating the same by alternate pulling on said chains, and thermostatic control mechanism operating to delay the circuit-breaking movement of the switch responsive to the manual actuation thereof.
- 55 2. A lamp socket switch having a casing and switch operating instrumentalities, the latter including contacts, a thermostat disposed circumferentially in the plane of said contacts a contact-controlling member pivoted to swing in the plane of said contacts and having an actuating segment removed from said plane, operatively different flexible pull members extending into the casing in a plane with said segment for oscillating the contact-controlling member by alternate

pulling thereon, and thermostatic control mechanism operating to delay the circuit-breaking movement of the switch responsive to the manual actuation thereof.

3. A lamp socket switch having spaced porcelains contacts operating therebetween, a contact-controlling member, brackets connecting said porcelains and one affording a pivot for said member a pull segment connected to the member and having a greater path of swing than the segmental space between said brackets, two operatively separate flexible pull members connected to opposite ends of said segment for oscillating the same, and a thermostatic contact control mechanism.

4. A lamp socket switch having spaced porcelains contacts operating therebetween, a contact-controlling member, brackets connecting said porcelains an oscillatory pull chain segment for actuating said member and having a greater arc of travel than the space between adjacent brackets, a pull chain for moving said segment, and thermostatic control means to delay the circuit-breaking movement of the contact responsive to manual actuation thereof.

5. A lamp socket switch having spaced porcelains and a removable enclosing casing and having also switch operating instrumentalities, the same including a pivoted combined cam-and-segment member, two operatively separate pull chains connected to said member for oscillating the same, a bell mouth guide for guiding said chains through said casing and helping to space and support said porcelains, and thermostatic control mechanism operative to delay the circuit-breaking movement of the switch responsive to the manual actuation thereof.

6. A lamp socket switch having spaced porcelains and a removable enclosing casing and switch operating instrumentalities, including a controlling member, a segment for actuating said member, a flexible pull member connected to said segment, a bell mouthed guide for said pull member extending between and helping to space and support said porcelains, and thermostatic control mechanism to delay circuit-breaking movement of the switch responsive to the manual actuation thereof.

7. A pull-chain operated electric switch mechanism having switch contacts designed to occupy a cylindrical enclosure and embodying a curved switch-controlling thermostatic band disposed circumferentially of said enclosure; and a pull-chain operated segment for controlling the switch contacts, said segment oscillating in the direction of curvature of said thermostatic band and in a plane adjacent the edge thereof.

8. In a thermostatically controlled pull-chain socket switch including a pivoted switch-operating segment to which the pull

chain is attached, the relative arrangement of a controlling thermostatic band and of said operating segment wherein the former is curved and disposed substantially circumferentially of the pivot of the latter and wherein said operating segment has a peripheral edge adjacent to and conforming to the curved edge of said thermostatic band.

10. 9. A socket switch mechanism embodying in combination a socket body, switch contacts, a curved thermostatic band arranged to govern, in part, the movement of the switch contacts responsive to manual actuation of the switch, a pivoted switch-operating segment having an anchorage for two operatively separate pull chains at respectively opposite peripheral ends, and carrying a peripheral channeled guide for said chains; a chain-outlet bell-guide secured to the socket body in a position opposite and closely adjacent the segment-carried chain guide, so that said segment is oscillated by alternate pulling on said separate chains.
15. 10. A pull-chain operated switch embodying, in combination; switch contacts, top and bottom insulating buttons connected by metallic bracket members secured thereto, one of said members having a flattened terminal disposed parallel to said buttons and between and spaced from same; and a pull operated member for actuating the switch contacts having a forked hub portion adapted to straddle the said bracket terminal 30 for pivotal mounting thereon together with a thermostatic device to govern in part the switch contacts.

11. A socket switch having switch contacts, a bracket terminal; a screw carried in a tapped hole substantially central of said terminal and having its end protruding therefrom, a spring-armed washer clamped under the head of said screw and against the face of said bracket terminal opposite the protruding end of said screw, a pivoting member for controlling said contacts having its hub formed by two-spaced flanges one of which has a hole fitting the protruding end of said screw and the other of which takes the thrust of said spring-armed washer,—the action of said washer pressing the first mentioned flange against the said bracket terminal and maintaining pivotal engagement between said hole and the protruding end of said screw and a thermostatic device to govern in part the switch contacts.

12. A socket switch having switch contacts, a bracket terminal; a pivot projection on the face of said terminal and substantially central thereof; an axially acting spring member bearing against the face of said bracket terminal opposite said projection; a pivoting member for controlling the contacts having its hub formed by two-spaced flanges, one of which has a hole fit-

ting said pivot projection, and the other of which takes the thrust of said spring-armed washer,—the action of said washer pressing the first mentioned flange against the said bracket terminal and maintaining pivotal engagement between said hole and said pivot projection and a thermostatic device to govern in part said contacts.

13. A socket switch having switch contacts, a rotatable contact controlling member, a pivotal support therefor, resilient devices acting normally to maintain pivotal engagement between the controlling member and its support but yieldable to permit intentional displacement laterally with relation thereto, and thermostatic mechanism to govern in part said contacts.

14. A socket switch having switch contacts, a rotatable contact controlling member and bearing seat on which it is pivotally supported, resilient means exerting an axial thrust to maintain pivotal engagement but yieldable to permit removal of said contact controlling member from said bearing seat or installation thereon, and thermostatic mechanism to govern in part said contacts.

15. In an electric switch, in combination; a leaf contact member, a latch to retain said member in a sprung position; a cam for forcing said contact into said position, and adapted to retract from contact with said member when the latter is held by said latch; and resilient means comprising an electrically active contact and acting to hold said cam fully retracted from said member when the latter is retained by said latch and thermostatic means for controlling said latch.

16. In an electric switch, in combination; a spring-leaf contact member; a latch to retain said member in a sprung position, a pivoted rectangular cam for forcing said member into its said position and adapted to retract from contact with said member by a quarter turn when the latter is held by said latch; and resilient means comprising an electrically active contact and acting to hold said cam fully retracted from said member after its said quarter turn and thermostatic means for controlling said latch.

17. In an electric switch, the combination with a spring contact member, a rotatable wiper contact movable into and out of engagement with said member and adapted to force the latter into sprung position, a thermostatically controlled device to retain said contact member in its sprung position, and means comprising an electrically active contact tending to restore the wiper contact to its disengaged position.

18. In an electric switch, the combination with a spring contact member, a rotatable wiper contact movable into and out of engagement with said member and adapted to force the latter into sprung position, and a

- thermostatically controlled device to retain said member in its sprung position, said switch being provided with means comprising an electrically active contact to locate 5 said wiper contact definitely in its engaged and disengaged positions and to restore it to its disengaged position in the event of an incomplete movement toward its engaging position.
- 10 19. In an electric switch, the combination with a spring contact member, a rotatable wiper contact movable into and out of engagement with said member and adapted to force the latter into sprung position, a thermostatically controlled device to retain said member in its sprung position, and a resilient device embodying an electrically active contact operatively related to said wiper contact and acting both to locate said contact definitely in its engaged and disengaged positions and to restore it to its disengaged position in the event of an incomplete movement toward its engaging position.
- 15 20. In an electric switch, the combination with a spring contact member, a rotatable wiper contact movable into and out of engagement with said member and adapted to force the latter into sprung position, and a thermostatically controlled device to retain said member in its sprung position, said switch being also provided with an auxiliary contact engaged by said wiper contact, said auxiliary contact being resilient and serving to restore said wiper contact to its 25 position of disengagement from said contact member in the event of an incomplete movement toward its engaging position.
- 20 21. In an electric switch, the combination with a spring-leaf contact, a rotatable contact-actuating member for engaging the same, manual means for moving said member, thermostatically controlled mechanism to govern in part said contact, and means comprising an auxiliary contact and tending normally to restore the contact-actuating member to a position of contact disengagement.
- 25 22. In an electric switch, the combination with a main spring leaf contact, a rotatable contact-actuating member for engaging the same, manual means for moving said member, thermostatically controlled mechanism to govern in part said contact, and means to locate said contact-carrying member in definite 30 positions of engagement or disengagement with said stationary contact, comprising an auxiliary and electrically active spring leaf contact.
- 35 23. An electric switch having in combination contacts including a rotatable conductive cam, and a spring leaf contact member co-operating therewith, an insulating facing secured to the surface of said member adjacent said cam by a conductive fastening, either said facing or its said conductive fastening being at all times pressed into contact with said cam in respectively different positions of the latter and thermostatic means to govern in part said contacts.
- 40 24. An electric switch having in combination contacts including a rotatable conductive cam and a spring leaf contact member co-operating therewith, a construction and arrangement of said cam and member wherein, the member is mounted to press against the cam in all positions of the latter and carries an insulating facing adapted to break electric contact between said cam and said member in predetermined relative positions thereof and thermostatic means for governing in part said contacts.
- 45 25. In an electric switch, a spring-leaf contact designed to be wipingly engaged by a co-operating movable contact member and for this purpose provided with a lengthwise stiffening formation extending from its point of mounting to a resilient terminal portion adapted to contact resiliently with said member and a thermostatically controlled device for governing one of said contacts.
- 50 26. In an electric switch, the combination with a spring leaf contact, a second spring leaf contact, a movable contact controlling member adapted by its movement to force the second contact into engagement with the first contact, and a thermostatically controlling device temporarily to hold the contacts in their sprung position of engagement, said second contact when released having a restoring movement transverse to the restoring movement of the first contact.
- 55 27. In an electric switch, the combination with a spring leaf contact, a second spring leaf contact, a movable contact controlling member adapted by its movement to force the second contact into engagement with the first contact, and a thermostatically controlling device temporarily to hold the contacts in their sprung position of engagement, said contacts when released having restoring movements in different directions.

Signed at Boston, in the county of Suffolk and Commonwealth of Massachusetts, this 29th day of November, 1920.

RAYMOND D. SMITH.
